UNITED STATES PATENT OFFICE.

SALLIE T. ANDRUS, OF AURORA, ILLINOIS.

COMBINATION TRUNK, BUREAU, AND WRITING-TABLE.

SPECIFICATION forming part of Letters Patent No. 521,873, dated June 26, 1894.

Application filed February 27, 1894. Serial No. 501,658. (No model.)

To all whom it may concern:

Be it known that I, SALLIE T. ANDRUS, a citizen of the United States, residing at Aurora, in the county of Kane and State of Illinois, have invented a new and useful Combination Trunk, Bureau, and Writing-Table, of which the following is a specification.

This invention relates to combination trunks; and it has for its object to provide certain improvements in combination trunks of that character which are adapted to combine therewith a construction adapting the article for use as a traveling trunk, a bureau, a writing table, and for other convenient uses which might suggest themselves.

To this end therefore the invention primarily contemplates a combination trunk and bureau of a simple and convenient construction especially adapting the same for the purposes required of it.

With these and other objects in view which will readily appear as the nature of the invention is better understood, the same consists in the novel construction, combination and arrangement of parts hereinafter more fully described, illustrated and claimed.

In the accompanying drawings:—Figure 1 is a perspective view of a combination trunk and bureau constructed in accordance with this invention, shown in its closed position. Fig. 2 is a similar view showing the cover thrown open in position for use as a table, and adapting the article for use as a bureau. Fig. 3 is a vertical transverse sectional view of the combined trunk and bureau showing the removable drawer frame partly slid out from the body of the trunk as in the act of removal. Fig. 4 is an enlarged central longitudinal sectional view showing the construction and adaptation of the folding legs.

Referring to the accompanying drawings, A represents a substantially rectangular trunk-body constructed in substantially the same shape and sizes as ordinary traveling trunks, and this trunk body consists of the rear side wall B, the opposite end walls C, and the top and bottom walls D and E, respectively, which are assembled together in any suitable manner and leave a front opening at one side which is adapted to be inclosed by the hinged front cover F. The front cover F, is hinged at its upper edge to the front edge of the top

wall D, on the strap hinges G, placed at suitable distances apart and forming a secure connection between the cover and the top of the trunk, and when closed the upper edge of said cover is adapted to fit beneath the top flange plate H, which projects from the upper front edge of the top wall D, and serves to close in the top joint of the cover and prevent dampness and dust from working its way inside of the trunk, and to the opposite side edges of the cover F, are attached the flanged corner plates or strips I, which embrace the opposite side edges of the trunk body, when the cover is closed and act in the same capacity as the top flange plate H, to cover the side joints when the cover is closed and keep out dampness and dust.

The front cover F, incloses the entire front opening of the trunk body, and, when closed, fits snugly over the upper edge of the front bottom strip J, attached to the front bottom edge of the trunk body to receive the bolt of the cover lock K, fitted in the swinging edge of the cover to provide for locking the same closed, and the cover is additionally secured in its closed position by means of the pivoted latch plates L, pivoted at l, to the outside of the cover F, and provided with finger flanges l', and rounded cam edges l'', which are adapted to be moved in rear of the heads of the headed catch studs or pins l'', projected from the front bottom strip J.

The construction just described substantially completes the main body of the trunk to adapt the same for the reception of goods when the trunk is used simply for traveling purposes, and in order to give sufficient strength to the trunk the corner edges of the same are suitably bound with the corner binding strips M, while the body of the trunk may be encircled by any number of suitable strengthening bands, such as are ordinarily employed in trunks of this character, and at opposite ends of the trunk body are arranged the usual flexible handles N, which provide convenient means for readily handling or moving the trunk in the ordinary manner, and as thus formed and adapted for use in traveling, the trunk may be set in any convenient position for packing and unpacking the same.

To adapt the trunk for use as a bureau the

opposite end walls C, thereof are provided with the opposite parallel pairs of supporting grooves O, which are adapted to removably receive the opposite projecting ends of the removable drawer or shelf frame P. The removable drawer or shelf frame P, is capable of being readily removed and replaced within the body of the trunk and consists of the parallel shelves p, permanently or rigidly connected together by a series of intermediate partition boards p', which not only provide means for permitting both shelves to be drawn out at the same time, but at the same time provide spaces or openings to receive suitable drawers p², some of which may be larger than others to accommodate hats and bonnets, or other similar articles, while the smaller drawers may be used for such articles as shoes, slippers, stockings, &c., and the 15 smaller drawers are preferably separated from each other by a separate horizontal partition wall p³, the side edges of which are joined to any two of the partition boards p', as clearly illustrated in Fig. 2. of the drawings.

The parallel shelves p, of the removable drawer or shelf frame P, are provided near their outer edges with the finger notches Q, to permit the fingers to easily grasp the said 20 drawer or shelf frame and slide the same entirely out of the body of the trunk when so desired, as illustrated in Fig. 3. of the drawings, and when in position within the trunk body with the several drawers properly in 25 position, it will be readily apparent that convenient means are provided for placing various articles properly away, and therefore adapting the trunk for use as an ordinary bureau, while at the same time by throwing 30 the cover F, back over the top of the trunk, a flat top table is provided which may be conveniently used for writing or any other purpose desired.

The combination character of the herein-described trunk necessarily involves means 35 for easily moving the same from place to place, and to provide for this, I hinge to opposite bottom portions of the trunk body, or at least to the bottom wall E, the hinged legs 40 R. The legs R, are hinged on the hinges r, to the bottom of the trunk, whereby the same can be folded flat against the bottom of the trunk and entirely inclosed within the encircling bottom flange S, projected from the 45 bottom of the trunk and partly formed by the front bottom strip J. The said legs R, are provided with the opposite feet T, depending from each extremity thereof and carrying the caster rollers t, to insure the easy 50 moving of the trunk, and at an intermediate point between their feet, the said legs are provided with the curved or rounded transverse grooves U, extending from diagonally opposite corners and terminating in the abrupt engagement shoulders u, and, as the 55 legs are unfolded to lower their feet from within the flange S, the grooves U shift the

engagement of the lock springs V. The 60 springs V, are ordinary leaf metal springs secured fast as at v, to the bottom of the trunk 65 and are provided near their outer free ends with the off-standing locking flange or lip W, doubled out from the body of the springs and adapted to engage at one side of either shoulder extremity u, of the grooves U, to hold the 70 legs locked in their folded and unfolded positions. When the legs are folded flat against the bottom of the trunk body a portion of the springs V, fit in the grooves U, and the flange or lips W, engage at one side of one 75 of the shoulder extremities u, and prevent the legs from becoming accidentally disarranged. By depressing the free end of the 80 spring to carry the flange or lip out of engagement with the legs in their folded position, said legs may be unfolded and brought to a position resting at one side against the 85 end portions of the flange S, and this position allows the flange or lip W, to drop in engagement behind the other shoulder extremity of the legs to hold the same locked in this 90 position also. A finger flange X, extends beyond the locking flange or lips W, of the 95 spring, to provide for manipulating the same.

Changes in the form, proportion and the 100 minor details of construction, may be resorted to without departing from the principle or sacrificing any of the advantages of this invention.

Having thus described the invention, what 105 is claimed, and desired to be secured by Letters Patent, is—

1. In a trunk, the combination of the substantially rectangular trunk body consisting of the rear side wall, opposite end walls and 110 a top and bottom wall, and provided at its front lower edge with a bottom strip, a top flange plate projected from the upper front edge of the top wall of the trunk body, a hinged front cover hinged at its upper edge 115 to the front top edge of the trunk and provided at its opposite side edges with flanged corner plates adapted to embrace the opposite side edges of the trunk body, headed catch 120 studs or pins projected from said front bottom strip, and latch plates pivoted to the cover and provided with rounded cam edges adapted to engage in rear of the edge of said studs or pins, substantially as set forth.

2. In a combined trunk and bureau, the 125 combination of a substantially rectangular trunk body provided with a hinged trunk cover, and having in its opposite end walls opposite pairs of parallel supporting grooves leading out to the front side edges of the 130 body, a removable and replaceable drawer frame comprising parallel shelves and a series of intermediate partition boards permanently or rigidly connecting said shelves, the latter being provided with projected ends adapted to loosely engage in said supporting grooves and finger notches near their front edges, said 135 drawer frame occupying an intermediate portion of the trunk body and when removed

leaving the trunk space unoccupied, and suitable drawers or trays arranged for support between the shelves of the removable drawer frame and providing a part of such frame so 5 as to be removed therewith when desired, substantially as set forth.

3. In a trunk of the class described, the combination with the trunk body having an encircling bottom flange, of opposite legs 10 hinged to opposite bottom portions of the trunk body and adapted to be folded within said encircling bottom flange, said legs being provided at their extremities with opposite feet carrying caster rollers, and at a point in- 15 termediate of the feet with rounded transverse grooves terminating at diagonally opposite

points in abrupt engagement shoulders, and metal lock springs secured to the bottom of the trunk body at one end and provided near their opposite free ends with locking flanges 20 or lips doubled out therefrom and adapted to engage at one side of either shoulder extremity of said grooves, said springs normally bearing in said grooves in either position of the legs substantially as set forth. 25

In testimony that I claim the foregoing as my own I have hereto affixed my signature in the presence of two witnesses.

SALLIE T. ANDRUS.
